UNITED STATES PATENT OFFICE

GUY L. WHITEFORD, OF SALINA, KANSAS

DEVICE FOR HOLDING FIRE HOSE NOZZLES

Application filed March 30, 1929. Serial No. 351,443.

This invention relates to a holder for fire hose nozzles, the general object of the invention being to provide a bar having a hose clamp at its center, with a handle at one end and a point at its other end so that by turning the bar, the nozzle can be positioned to direct the water to any desired point, with a harness for supporting the bar from the shoulders of the firemen.

10 This invention also consists in certain other features of construction and in the combination and arrangement of the several parts, to be hereinafter fully described, illustrated in the accompanying drawings and specifically 15 pointed out in the appended claim.

In describing the invention in detail, reference will be had to the accompanying drawings wherein like characters denote like or corresponding parts throughout the several 20 views, and in which:—

Figure 1 is a view showing the device in use and handled by two firemen.

Figure 2 is an elevation of the device alone.

Figure 3 is an edge view thereof.

25 Figure 4 is a view showing the device handled by one fireman.

As shown in these views, the device comprises a bar 1 having a point 2 at one end and a handle 3 at its other end. The central 30 part of the bar is flattened and the middle of the flattened portion is bent into semi-circular form, as shown at 4. A semi-circular part 5 is hingedly connected with one end of the part 4, as shown at 6, and the other end of 35 the part 5 is detachably connected with the flattened part adjacent the part 4 by a bolt and nut 7 or in any other suitable manner. A plurality of rings 8 is carried by the bar 1, these rings passing through holes formed 40 in the bar. Straps 9, each adjustable as to its length, have snap hooks 10 at each end thereof for engaging the rings.

Thus it will be seen that the hose connection of the nozzle 11 of a hose 12 can be easily 45 and quickly attached to the bar by swinging the part 5 away from the part 4, placing the connection in the part 4 and then closing the part 5, whereby the nozzle is clamped to the bar. The straps are placed around 50 the shoulders of the firemen, as shown in

Figure 1, and by one fireman turning the bar through means of its handle 3, the nozzle can be adjusted to throw the water to any desired point. This is clearly shown in Figure 1. When a single fireman is to manipulate 55 the hose, one of the straps is removed and the pointed end of the bar is driven into the surface, as shown in Figure 4, with the strap passing around the shoulder of the fireman. Then by turning the bar through means of 60 its handle, the nozzle can be adjusted as before.

With this invention, one or two firemen can readily hold the nozzle of a hose without danger of its getting away from them and 65 by turning the bar by its handle, the firemen can direct the water from the nozzle laterally or vertically at any angle.

It is thought from the foregoing description that the advantages and novel features 70 of the invention will be readily apparent.

It is to be understood that changes may be made in the construction and in the combination and arrangement of the several parts, provided that such changes fall within 75 the scope of the appended claim.

What I claim is:—

A device for holding fire hose nozzles comprising a bar having one end pointed, a handle formed intermediate its ends with the 80 outer end of the bar, a hose attaching means located on the bar intermediate the ends of the latter, spaced rings on the bar at opposite sides of the hose attaching means, adjustable shoulder straps having one end of each strap 85 connected to the rings at one side of the hose attaching means and the other end of each strap connected to the rings at the opposite side of the hose clamping means with the straps passing over opposite shoulders of persons supporting the bar horizontally and in front thereof.

In testimony whereof I affix my signature.

GUY L. WHITEFORD.
